AMUSEMENT DEVICE

Leon S. Harris, P.O. Box 10445, Raleigh, N.C.

Filed Aug. 27, 1958, Ser. No. 757,478

1 Claim. (Cl. 273—97)

The present invention generally relates to an amusement device and more particularly and to that type of amusement device having a paddle or bat of a generally flat construction with a ball attached thereto by virtue of an elastic or rubberband together with a target incorporated into the bat or paddle and a noise producing mechanism connected with and operated by the target for producing a noise when the ball strikes the target, thereby providing a highly entertaining amusement device as well as one in which there is provided a mechanism for immediately indicating the striking of the target by the ball with certain skill being developed and entertainment being provided by an operator trying to strike the target with the ball.

An object of the present invention is to provide an amusement device in the form of a paddle having a handle thereon together with an elastic band connected to the paddle and having a rubber ball mounted on the outer end thereof with the paddle incorporating a rubber bulb of hollow construction attached thereto and forming a target for the ball.

A further object of the present invention is to provide an amusement device in accordance with the preceding object in which the hollow rubber bulb is communicated with a whistle mounted on the other side of the paddle whereby a whistling sound will be produced by the whistle when the ball strikes the bulb, thus providing a highly entertaining amusement device as well as providing one which more rapidly develops the skills of the players or operators.

Another object of the present invention is to provide an amusement device which is extremely simple in construction, highly entertaining, easy to use, capable of many possible variations and relatively inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a plan view of the amusement device of the present invention as viewed from the target and ball side;

Figure 2 is a plan view of the amusement device as viewed from the rear side or whistle side;

Figure 3 is a vertical sectional view taken substantially upon a plane passing along section line 3—3 of Figure 1 illustrating the details of construction of the paddle and related target and whistle;

Figure 4 is a sectional view on an enlarged scale taken substantially upon a plane passing along section line 4—4 of Figure 2 illustrating further structural details of the bulb and whistle mechanism;

Figure 5 is a transverse, sectional view taken substantially upon a plane passing along section line 5—5 of

2

Figure 4 illustrating further structural details of the device;

Figure 6 is a perspective view of the whistle unit per se which is removed from the paddle illustrating the construction thereof;

Figure 7 is a sectional view similar to Figure 4 but showing a modified form of whistle with a modified manner of attachment; and

Figure 8 is an exploded group perspective view of the whistle and its relationship to the paddle of Figure 7.

Referring now specifically to Figures 1—6 of the drawings, the numeral 10 generally designates the amusement device of the present invention which includes a generally flat paddle 12 having a circular area 14 and a laterally extending handle 16 extending from one side thereof in the same plane. The paddle may be constructed of any suitable material such as wood or the like and is provided with a staple or other fastening member 18 adjacent the center of the circular area 14, the staple 18 securing an elongated elastic band or rubberband or member 20 thereto. The elastic band or member 20 is connected to a rubber ball 22 at the outer end thereof. Thus by manually operating the paddle 12 in a manner well known, the ball 22 may be engaged with the circular area 14 of the paddle 12 for causing sequential inward and outward movement of the rubber ball and alternate stretching and relaxing of the elastic band 20.

Disposed centrally in the circular area 14 of the paddle 12 is an opening 24. Overlying the opening 24 and disposed on the same side of the paddle 12 as the fastening staple 18 is a generally semi-spherical hollow rubber bulb 26 which is provided with an outwardly extending peripheral flange 28 which engages the surface of the paddle 12 and is bonded thereto as by gluing or the like. The flange 28 tapers to a sharp marginal edge for facilitating the gluing of the rubber bulb 26 to the surface of the paddle 12 in such a manner that the only way for air to pass into and out of the hollow bulb 26 is through the opening 24. The bulb 26 provides a target or ball's eye of less area than the surface area of the paddle. The area of the paddle disposed peripherally of the bulb forms a striking area for the ball. Engagement of the rubber ball 22 with the bulb 26 causes momentary collapse of the bulb 26, thus causing air to be expelled outwardly therefrom through the opening 24. As soon as the ball 22 bounces away, the natural resiliency of the rubber bulb 26 will cause the same to move to its original position thus drawing air back through the opening 24 into the interior of the bulb 26.

While the rubber bulb has been shown with the flange 28 glued to the surface of the circular area 14, many alternative methods could be provided for mounting the bulb 26 in position. For instance, the area adjacent the aperture 24 could be recessed so that the flange would fit in the recess thus providing a smooth surface for the paddle except for the semi-spherical portion of the bulb.

Mounted in overlying relation to the opening 24 on the opposite side of the paddle 12 from the bulb 26 is a generally semi-cylindrical member 30 having a closed end 32 and an open end 34 and a transverse partition 36, the edges of the partition 36, closed end 32 and the member 30 being secured to the surface of the paddle as by gluing or any other suitable fastening means. The portion of the generally semi-cylindrical member 30 between the closed end wall 32 and the partition 36 communicates with the opening 24, the inner edge of the partition 36 being generally in alignment with the edge of the opening 24 as shown in Figure 4.

The partition 36 is provided with a generally channel shaped tone block 38 provided with a reed or vibrator

40 disposed against the upper surface thereof, the tone block 38 having an upwardly curved and generally closed end portion 42 disposed adjacent the open end 34 of the semi-cylindrical member 30. The generally U-shaped and elongated tone block 38 having the inwardly curved end 42 together with the vibrator or reed 40 provide a whistle so that as air passes between the reed 40 and the curved end 42 inwardly towards the opening 24, the whistle will be blown. When the ball initially contacts the bulb 26, air will be expelled from the bulb out through the whistle which will not cause vibration of the reed. However, when the ball moves away and the bulb returns to its normal position, the air will be replaced in the bulb 26 by rapid movement through the tone block by passing initially between the free end of the tone block and the free end of the reed 40 thus setting up vibrations in the reed 40 for producing a whistling noise. Thus, each time the ball strikes the bulb there will be an exhaust of air but during the subsequent intake of air, the whistle will be blown or operated.

The open end of the tone block of the whistle faces the opening 24 so that the reed will vibrate only when the air is returned into the bulb and not when the bulb is struck and depressed. This eliminates any possibility of the reed jamming in the event air in the bulb is compressed very rapidly or too suddenly when the bulb is struck by the ball. Inasmuch as it is possible that air will jam in the bulb if the air is not permitted to escape fast enough through the whistle unit, there may be provided an escapement valve in the form of a check valve or the like to allow the air to pass out quickly no matter how hard the bulb is depressed.

Referring now specifically to Figures 7 and 8, the numeral 12' illustrates a paddle similar to the paddle 12 in Figure 1, the opening 24', the bulb 26' and flange 28' being the same. In this form of the invention, the whistle includes a cylindrical extension 44 having a circular plate 46 at one end thereof and an outwardly flared horn-like element 48 extending therefrom. The cylindrical extension 44 is telescopically received and frictionally held in the opening 24 or may be rigidly secured therein in any manner. The inner end of the cylindrical member 44 as well as the plate 46 extends inwardly and forms a partition wall 50 having a tone block 52 and reed 54 overlying the same extending therethrough with the open end of the tone block 52 facing the bulb 26' and the closed end thereof facing the free end of the flared member 48. The operation of the whistle defined by the tone block 52 and 54 is the same as in Figures 1-6 so that air moving outwardly from the bulb 26' due to compression thereof when the ball strikes the bulb 26' will not cause vibration of the reed 54 but the reed 54 will produce a whistling sound when air returns into the bulb 26'. All parts of the whistle may be constructed of plastic except for the reed which is constructed of metal. The tone block may or may not be constructed of metal but is preferably of metal as is the reed or vibrator 40.

In each instance, the whistle may be glued, nailed or otherwise fastened to the paddle and the elements of the whistle including the tone block and reed may be embedded in the partition wall of the whistle thus assuring continuous and proper relationship between the reed and tone block for producing a whistling noise when the air bulb is engaged by a ball.

While the illustrations in the drawings have been restricted to whistle type of sound producing mechanism, the present invention also incorporates the arrangement in which a bell type unit may be employed for the

whistle, such a bell unit incorporating a plunger movable in relation to a bell and the plunger being operable in response to an increase in pressure in the air bulb, such compression of air forcing the plunger against the bell to sound the same. Further, the whistle construction may be such that the device may produce a whistling sound either when air moves out of the bulb or when air moves into the bulb.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

In a tethered ball and paddle type amusement device, the combination of a paddle provided with an opening, 20 a semi-spherical hollow and resiliently compressible bulb mounted on one side of said paddle and having said opening in communication with the interior thereof, said bulb covering only a minor portion of the surface area of the paddle thereby defining a target on the paddle, 25 the surface area of the paddle extending peripherally outwardly of the bulb and forming a striking area extending completely around the periphery of the bulb, an outturned marginal flange provided on said bulb and secured to said paddle, an elongated resilient flexible 30 tethering element secured at one end thereof to the paddle at a point adjacent to but spaced from the flange of said bulb, a resilient ball mounted on the other end of said tethering element and adapted to impact against the striking area of the paddle or said bulb to collapse the latter, and a whistle disposed at the relatively opposite side of said paddle, said whistle including an elongated tone block having an outer end communicating with the atmosphere and an inner end in communication with the interior of said bulb through said opening whereby 35 air may be discharged from the interior of the bulb into the atmosphere when the bulb is collapsed by impact of said ball thereagainst, and a vibratory reed provided on the outer end of said tone block, whereby upon relaxation of said bulb ingress of air from the 40 atmosphere through the tone block may sound the whistle, a whistle housing carried by said paddle and having said tone block and reed mounted therein, said housing including a partition wall, said tone block and reed extending through the partition wall, the partition wall 45 forming the sole supporting means for the tone block and reed and spacing the same from the inner surface of the housing, said whistle housing comprising a substantially semi-cylindrical body having its flat side secured to said paddle and having a closed end and an open end, 50 said partition wall disposed intermediate the ends of said body and separating the same into a closed end portion in communication with said opening and an open end portion in communication with the atmosphere, said partition wall being provided with an aperture having 55 said tone block and reed mounted therein, whereby the inner and outer end portions of the tone block are disposed respectively in the closed end and the open end portions of said body.
